CAR BRAKE

Louis G. Miller, Bethlehem, Pa., assignor to
Bethlehem Steel Company, a corporation of
Pennsylvania

Application December 31, 1935, Serial No. 56,920

32 Claims. (Cl. 188—107)

My invention relates to improvements in car brakes and is adapted more particularly for use in connection with mine cars and for similar small cars of this type in which the braking of the cars is hand operated.

In the majority of mine tunnels on account of room there is a siding only on one side and the brakes have to be operated from that side of the car, and as mine cars sometimes obtain a speed 10 as great as 15 miles per hour in transit, and since the mine laws forbid a riding operator, one is stationed at a point along the track where the car is to be brought to a stop.

It is often found necessary, however, to set the 15 brakes from the opposite side of the car to that of the siding but on account of lack of space between the car and the side of the mine tunnel there is not room enough for this purpose, or in some cases the brake operating side of the car 20 in passing through the mine tunnels is on the opposite side to that of the siding where the operating lever can not be reached by the operator.

The operator waiting on the siding by the track 25 for the car to pass must grasp the operating lever of the passing car, and to avoid injury, he must run along with the moving car, and pull the brake operating lever at the same time, should there be any wear in the operating lever 30 ratchet teeth or between the brake shoes and the wheels, either the brake shoes would grip the wheel treads before the operating lever engages the proper ratchet tooth and then slack off after the operator releases the operating lever, 35 or the brake shoes at their maximum movement would not have proper contact with the wheels.

As this braking operation must be accomplished not only on the surface but in the darkened interiors of the mine tunnels, and when it 40 is remembered that these operations of braking mine cars must be repeated by an operator several hundred times a day that the mechanism employed for braking cars should be safe, sure and easily operated and will reduce to a minimum 45 the hazards heretofore encountered.

Heretofore mine cars have had a single operating lever usually pivotally connected and disposed centrally, which is difficult for the operator to reach, or at one side only of the end of the car for actuating the brake shoes. One of the objects of my invention is to provide a braking mechanism that is capable of self-adjustment to compensate for any slight differences in 50 lengths of connections or unequal wear on the 55 brake shoes or blocks, thus obtaining equal pres-

sure of the shoes or blocks on the wheels at both sides of the car.

Another object of my invention relates to a braking mechanism which can be easily applied or released from either side of the car. 5

A further object of the invention relates to the manner of actuating the operating lever so that the ratchet tooth will have proper engagement with the teeth of the rack plates and will not slack off after the operator releases the operating lever. 10

Another object of my invention relates to the manner of attaching a pair of operating levers to the opposite sides of the end of a car so they will each have a floating fulcrum connection. The levers being connected together above and below the fulcrum points by means of equalizing links, so that when one lever is operated the other will be moved in unison but in the opposite direction. 15

Another object of my invention relates to the manner of operating the rock shafts simultaneously or independently of each other so that the pressure of the brake shoes when applied will be fully equalized on the wheels at both sides 20 of the car. 25

The invention also has for its object a simple mechanism of this character which may be easily installed on mine cars or the like of any ordinary or conventional type, the parts being strong 30 and durable and not liable to get out of order, and the invention aims to generally improve this class of devices and to render them more useful and commercially desirable.

Having thus given a general description of my 35 invention, I will now in order to make the matter more clear, refer to the accompanying four sheets of drawings, forming a part of this specification in which like characters of reference indicate corresponding parts in all the figures. 40

Fig. 1 is a side elevation of a mine car or the like with braking means applied thereto embodying one form of my invention.

Fig. 2 is an end elevation of the car shown in Fig. 1. 45

Fig. 3 is an enlarged detail sectional view through the end portion of the car taken on the line 3—3 of Fig. 2, showing the equalizing mechanism applied thereto.

Fig. 4 is a detail view of one of the equalizing 50 rods.

Fig. 5 is an end elevation of a low level type of mine car to which a modified form of my invention is attached.

Fig. 6 is a transverse section of the car shown 55

in Fig. 5 taken centrally on the line 6—6 of Fig. 7.

Fig. 7 is a side elevation of the car with the modified form of my invention attached.

Fig. 8 is a detail plan view of the modified form of my equalizing device detached.

Fig. 9 is an enlarged detail section taken on the line 9—9 of Fig. 5, showing the manner of holding and releasing one of the brake levers.

Fig. 10 is a detail view of one of the racks and the adjacent portions of the device associated therewith, and

Fig. 11 is a detail view illustrating one of the tension springs and the parts connected therewith.

Referring now to the character of reference on the drawings, and first to Figs. 1 to 4. The numeral 1 indicates a mine car of the four-wheel type having a floor 2, side walls 3 and ends 4. 5 indicates the axles and 6 the wheels mounted 20 on the axles. A pair of brackets 7 extend downwardly from the floor between the wheels on each side of the car, to which is pivoted as at 8, the upper ends of hangers 9, having their lower ends pivoted as at 10 to brake shoes 11 which are 25 adapted to frictionally engage the tread surfaces of the wheels. Pivoted to each of the brake shoes 11, as at 12, are adjustable links 13, each pair of which on opposite sides of the car being inclined inwardly and have their upper ends pivoted, as 30 at 14, to the lower end of a clevis 15, while the upper end of said clevis 15 is pivoted, as at 16, to the outwardly extending end of a crank arm 17 of the rock-shaft 18. These rock-shafts 18 on each side of the car are mounted in bearings 19 and 20 and are held against longitudinal movement by the collars 21 and 22 formed integral therewith, which are adapted to engage the sides 35 of the bearings 19 and 20. The outer ends of the rock-shaft 18 project beyond the end of the car and are each formed with a crank arm 23 bent at right angles to the body of the rock-shafts and also at an angle to the crank arms 17. The ends of these two crank arms 23 are flattened and connected together by means of an 40 equalizing device which is actuated by means of a pair of operating levers 24 and 25 attached to the opposite sides of the car end near its lower portion by means of swinging arms 26 and 27. The top ends of each of said swinging arms are 45 pivoted to the end wall by means of a bolt or rivet 28, while the lower ends of the swinging arms are offset and formed cylindrical adapted to form floating fulcrum pivots 29, for the operating levers 24 and 25 near their lower ends, which 50 are secured thereon by means of a split pin 30.

A short distance above the floating fulcrum pivots 29 of each of the operating levers 24 and 25 is pivoted, as at 31 the inner ends of a stirrup 32, the outer central portion of each of which is perforated as at 33 for the passage of an adjusting rod 34 having a threaded portion 35 provided with an adjusting nut 36 located within the stirrup. Each of the adjusting rods 34 has an extending bifurcated end 37 which is pivoted to the flattened end of the crank arms 23 of the rock-shafts 18.

The legs of each stirrup 32 are connected together at an intermediate point by means of a transverse plate 38 which has its ends welded thereto and is perforated centrally as at 39 for the passage of the reduced ends 40 of the adjusting rods 34, and a helical spring 41 normally under compression is interposed between the adjusting nuts 36 and the transverse plates 38. 70 A pair of equalizing bars 42 crossing each other

centrally connect the operating levers 24 and 25 together. One end of each of said equalizing bars being attached at 31, while the opposite end is pivoted to the lower end of one of the operating levers at an equal distance below the floating fulcrum pivots 29 as at 43.

Each of the operating levers 24 and 25 are provided with a ratchet tooth 44 for engaging the teeth of racks 45.

Normally the tooth 44 of each of the operating levers will engage the teeth of the racks 45. When it is desired to disengage the tooth 44 of each of the operating levers from the racks 45 to release the brakes, the operator grasps the handle 46 of a crank shaft 47 and swings it upwardly so that the cranks 48 engage the inner faces of the operating levers 24 and 25 and forces them outwardly, thereby disengaging the tooth 44 of each operating lever from its rack 45. In this arrangement the equalizing mechanism is held by the springs under compression and it is also desirable in assembling to adjust the rods 34 so that when the brake shoes are released from the wheels the springs will be slightly compressed.

The operation of my braking mechanism is as follows: Assuming that the parts are in the position shown in the drawings, which is the position they will assume when the brake shoes are released, and it is desired to set the brakes, the operator grasps the handle of one of the operating levers 24 or 25 and pulls it outwardly in the direction of the arrows as indicated in Fig. 2, until the brake shoes engage the wheels. In so doing it will be understood that on account of the connecting equalizing bars 42 both of the levers will be actuated in unison but in the opposite directions.

In setting the brakes the springs 41 which are normally under compression may be slightly compressed but this is not necessary as the brakes will be set properly by the movement of the swinging floating fulcrum pivots without the springs, the prime object of the springs 41 are to insure the tooth 44 of each of the operating levers 24 and 25 to properly engage the teeth of the racks 45.

If the ratchet teeth 44 of the operating levers do not register with the teeth of the racks 45 when the brakes are set, a slight additional pull of the lever will compress the springs 41 and allow the tooth of each operating lever to properly engage the teeth of the racks. During the setting of the brakes if both of the rock-shafts 18 are rotated the same angle of rotation, the floating fulcrum pivots 29 for the operating levers will remain substantially stationary. If however on account of wear on the brake shoes or slight differences in adjustment of the connecting parts the brake shoes on the right hand side of the car, as viewed in Fig. 2, engage the wheels first the levers will continue to move swinging the floating fulcrum pivots from left to right until the brake shoes on the left hand side of the car properly engage the wheels. In case the brake shoes on the left hand side of the car engage the wheels first the floating fulcrum pivots for the operating levers will be moved from right to left. In either case the brake shoes will be finally applied with full braking force on all of the wheels at the same time.

When it is desired to release the brakes the operator grasps one of the handles 46 of the crank shaft 47 and swings it upwardly so that the cranks 48 engage the inner faces of the operating levers 24 and 25 and forces them outwardly

thereby disengaging the tooth of each operating lever from its rack 45, as indicated in dotted lines in Fig. 9. When the ratchet teeth of the operating levers are disengaged from the racks the 5 brake shoes will be released from engagement with the wheels by means of the torsional force exerted on the rock-shafts 18 in setting the 10 brakes. The helical springs 41 will at the same time assist in swinging the operating levers 24 and 25 inwardly, provided they have been further compressed at the end of the brake setting 15 operation. The parts will then by their own action be returned to the position indicated in Fig. 2.

15 Referring now to the modification illustrated in Figs. 5 to 11 inclusive in which I have shown the equalizing mechanism is held in tension instead of under compression as above described for Figs. 1 to 3.

20 In this modification the same operating levers, floating fulcrum pivots therefor, equalizing bars and release crank shaft are used and operated in a similar manner and the same reference numerals will apply thereto, and this also 25 may apply to the car and the mounting of the rock-shafts and the brake shoes, hangers and link connections therefor.

25 In this construction however the inner crank arms 49 of the rock-shafts 18 extend inwardly instead of outwardly as above described, and as 30 this is a low level car the upper ends of each pair of the adjusting links on each side of the car are pivoted as at 50 to the upper end of a clevis member 51 while the lower end of said 35 clevis member is pivoted centrally to a supporting bar 52 having one end pivoted to a rib 53 extending from the car floor while the opposite end is pivoted to a pair of short links 54 which in turn are pivoted to the end of each crank arm 49.

40 In this construction the inner ends of the stirrup members 55 are attached with one end of the equalizing bars to the lower ends of the operating levers 24 and 25 at the points 43 below the floating fulcrum pivots 29. The stirrup 45 members 55 extend outwardly from the operating levers and are perforated as at 56 for the passage of the adjusting rods 57 which have their inner ends threaded as at 58 and screwed into a threaded opening in the central portion of a sliding plate 59. The adjusting rods 57 each have a spring 60 interposed between the plate 59 and the end wall of the stirrup. The extending ends of the rods 57 are bifurcated as at 61 and pivoted to the crank arms 23 on the outer ends of the 55 rock-shafts 18.

55 The manner of operating this modified form of braking mechanism is the same as above described. The operator pulling one of the operating levers to set the brakes and then releasing the 60 brakes by manipulating the crank shaft. The difference being that as the equalizing mechanism is under tension, the stirrups are pulled inwardly to compress the springs 60 instead of being pushed outwardly where the equalizing mechanism is under compression as indicated in Figs. 1 to 3, and it will also be noted that the inner crank arms 49 of the rock-shafts 18 must extend inwardly instead of outwardly.

65 As illustrated, I prefer to use a pair of springs at each end of the equalizing device to give the most satisfactory results, but I may dispose the springs differently or use one spring instead of two if desired.

70 The operating levers are usually located on 75 the trailer end of the car but my device could

be applied and operated from the front end of the car equally as well, and although I have shown only one form of brake shoes and manner of mounting the same, I may use other forms of brake shoes and mountings than the type 5 shown in the drawings and obtain the same results.

75 Although I have described and illustrated my invention in considerable detail, I do not wish to be limited to the exact and specific details thereof, as shown and described, but may use such modifications in, substitutions for, or equivalents thereof, as are embraced within the scope of my invention, or as pointed out in the claims.

Having thus described my invention what I 15 claim as new and desire to secure by Letters Patent is:

1. The combination with a car body and a wheel at each side of the car, a rock-shaft arranged parallel to and supported on each side of the 20 car body, brake shoes pivotally connected to the rock-shafts for engaging each wheel, and a pair of operating levers pivotally connected to one end of the car and bodily movable simultaneously for actuating the rock-shafts adapted 25 to force the brake-shoes into or out of frictional engagement with the wheels.

2. The combination with a car body and wheels at each side of the car, a rock-shaft arranged parallel to and supported on each side of the 30 car, brake shoes pivotally connected to the rock-shafts for engaging the wheels, and a pair of operating levers connected together and pivoted to one end of the car and bodily movable simultaneously for actuating the rock-shafts adapted 35 to move the brake shoes into or out of frictional engagement with the wheels.

3. The combination with a car body and wheels at each side of the car, a rock-shaft arranged parallel to and supported on each side of the car 40 body, brake shoes pivotally connected to the rock-shafts for engaging the wheels, a pair of simultaneously bodily movable operating levers pivoted to one end of the car adapted to move the brake shoes into or out of frictional engagement 45 with the wheels, and a resilient connection between the operating levers and the rock-shafts.

4. The combination with a car body and a pair of wheels at each side of the car, a rock-shaft mounted on each side of the car body, brake 50 shoes pivotally connected to each rock-shaft for engaging the wheels, a pair of simultaneously bodily movable operating levers pivoted to one end of the car adapted to move the brake shoes into or out of frictional engagement with the 55 wheels, and a resilient connection between each operating lever and one of each of the rock-shafts.

5. The combination of a car body, and a wheel at each side of the car, a rock-shaft arranged 60 parallel to and supported on each side of the car body, a brake shoe pivotally connected to each rock-shaft for engaging each wheel, and a pair of operating levers having floating pivots secured to one end of the car and movable simultaneously 65 for actuating the rock-shafts adapted to force the brake shoes into or out of frictional engagement with the wheels.

6. The combination of a car body and a pair of wheels at each side of the car, a rock-shaft 70 arranged parallel to and supported on each side of the car body, brake shoes pivotally connected to each rock-shaft for engaging each pair of wheels, a pair of operating levers having floating fulcrums secured to one end of the car and mov- 75

able simultaneously for actuating the rock-shafts and adapted to force the brake shoes into or out of frictional engagement with each pair of wheels, bars having their ends pivotally attached to the operating levers and connecting them together, and a resilient connection between the operating levers and the rock-shafts.

7. The combination of a car body and a pair of wheels at each side of the car, a rock-shaft arranged parallel to and supported on each side of the car body, brake shoes pivotally connected to each rock-shaft for engaging each pair of wheels, a pair of operating levers having floating fulcrums secured to one end of the car and movable simultaneously for actuating the rock-shafts to force the brake shoes into or out of frictional engagement with each pair of wheels, equalizing bars connecting the operating levers, a resilient connection between the operating levers and the rock-shafts, means for holding the operating levers when the brakes are set, and means for simultaneously releasing both of the operating levers.

8. The combination of a car body and a plurality of wheels at each side of the car, a rock-shaft arranged parallel to and supported on each side of the car body, brake shoes pivotally connected to each rock-shaft for engaging each pair of wheels, a pair of operating levers each having floating fulcrum secured at opposite sides to one end of the car, said operating levers each having a connection with both of the rock-shafts, means when one of the operating levers is actuated for rotating both of the rock-shafts to force the brake shoes into or out of frictional engagement with each pair of wheels, means for holding the operating levers when the brakes are set, and means for simultaneously releasing both of the operating levers to automatically disengage the brake shoes from the wheels.

9. The combination with a car body and a plurality of wheels at each side of the car, a rock-shaft arranged parallel to and supported on each side of the car body, brake shoes pivotally connected to the rock-shafts, a pair of bodily movable operating levers connected together at opposite sides of one end of the car, each adapted when manually operated to force the brake shoes into or out of frictional engagement with the wheels, a resilient connection between the operating levers and the rock-shafts, and means for releasing the brake shoes from the car wheels.

10. The combination with a car body and a plurality of wheels at each side of the car, a rock-shaft arranged parallel to and supported on each side of the car body, brake shoes pivotally connected to the rock-shaft, a pair of operating levers each having a floating fulcrum mounted at opposite sides of one end of the car, equalizing bars connecting the operating levers, an adjustable resilient connection between each operating lever and a rock-shaft, means for holding the operating levers when the brakes are set, and means for releasing the brake shoes from the wheels.

11. The combination with a car body and a plurality of wheels at each side of the car, a rock-shaft mounted on each side of the car body, brake shoes pivotally connected to the rock-shafts for engaging the wheels, a pair of operating levers each secured by a floating fulcrum to opposite sides of one end of the car, equalizing bars connecting the operating levers, means for actuating the operating levers in unison in opposite directions, and a resilient connection be-

tween each operating lever and each rock-shaft.

12. The combination with a car body and a pair of wheels at each side of the car, a rock-shaft arranged parallel to and supported on each side of the car body, brake shoes pivotally connected to the rock-shafts, an operating lever pivoted to each side of the end of the car body, equalizing bars for connecting the operating levers, a resilient connection between each operating lever and one of the rock-shafts, said equalizing bars and resilient connections comprising means when one of said operating levers is manipulated for actuating both of the operating levers in unison in opposite directions to initially rotate both rock-shafts simultaneously and then to rotate one rock-shaft independently of the other rock-shaft.

13. The combination with a car body and wheels at each side of the car, a rock-shaft arranged parallel to and supported on each side of the car body, brake shoes pivotally connected to the rock-shafts for engaging the wheels, an operating lever pivoted to opposite sides of one end of the car adapted to be actuated from either side of the car, equalizing bars for connecting the operating levers, said equalizing bars comprising means when one of said operating levers is manipulated for actuating both of the operating levers in unison in opposite directions to initially rotate the rock-shafts simultaneously and then to rotate one rock-shaft independently of the other rock-shaft.

14. The combination with a car body and a pair of wheels at each side of the car, a rock-shaft arranged parallel to and supported on each side of the car body, brake shoes pivotally connected to the rock-shafts for engaging the wheels, an operating lever having a floating pivotal connection with one end of the car near the opposite side of the car, equalizing bars for connecting the operating levers, said floating pivotal connections and equalizing bars comprising means when one of said operating levers is manipulated for actuating both of the operating levers in unison to initially rotate both of the rock-shafts simultaneously and then to rotate one rock-shaft independently of the other rock-shaft.

15. The combination with a car body and a pair of wheels at each side of the car, a rock-shaft arranged parallel to and supported on each side of the car body, brake shoes pivotally connected to the rock-shafts for engaging the wheels, an operating lever disposed near the opposite sides of one end of the car each having a floating fulcrum connection with the car end and adapted to be actuated from either side of the car, equalizing bars for connecting the operating levers at an equal distance above and below the floating fulcrum connections of the operating levers, a resilient connection between the operating levers and the rock-shafts, said floating fulcrum connections, equalizing bars and resilient connections comprising means for simultaneously actuating both of said operating levers in opposite directions by the movement of either operating lever to initially rotate the rock-shafts simultaneously and then if required to rotate one rock-shaft independently of the other rock-shaft.

16. The combination with a car body and a pair of wheels at each side of the car, a rock-shaft arranged parallel to and supported on each side of the car body, brake shoes pivotally con-

5 nected to the rock-shafts for engaging the wheels, an operating lever disposed at opposite sides of one end of the car each having a floating pivotal connection with the car end and adapted to be
 10 actuated from either side of the car, equalizing bars for connecting the operating levers at an equal distance above and below the pivotal connection of the operating levers, a resilient connection between each operating lever and one of the rock-shafts, said floating pivotal connections, equalizing bars and resilient connections comprising means for actuating the said operating levers simultaneously to initially rotate both rock-shafts, and then if required to rotate one
 15 rock-shaft independently of the other rock-shaft, and means for releasing the brakes.

17. In braking means in combination with a car having wheels at each side thereof, a rock-shaft arranged parallel to and supported on each side of the car body, brake shoes pivotally connected to the rock-shafts, for engaging the wheels, an operating lever disposed near each side of the end of the car, a floating pivotal connection for attaching each operating lever to the car end, equalizing bars for connecting the operating levers, resilient means between the operating levers and the rock-shafts for holding the equalizing bars under compression, means for holding the operating levers when the brakes
 30 are set, and means for releasing the brake shoes from the wheels.

18. The combination with a car body and wheels at each side of the car, a rock-shaft arranged parallel to and supported on each side of the car body, brake shoes pivotally connected to the rock-shafts for engaging the wheels, a pair of operating levers having floating pivotal connections to opposite sides of one end of the car, means for actuating the operating levers in unison to move the brake shoes into or out of frictional engagement with the wheels, a resilient connection between each operating lever and one of the rock-shafts, means for holding the operating levers when the brakes are set, and
 45 means for releasing the brakes.

19. The combination with a car body and wheels at each side of the car, a rock-shaft arranged parallel to and supported on the side of the car body, brake shoes pivotally connected to the rock-shaft for engaging the wheels, a bodily movable operating lever pivoted to one end of the car for actuating the rock-shaft and a resilient connection between the operating lever and the rock-shaft.

20. The combination with a car body and wheels at each side of the car, a rock-shaft arranged parallel to and supported on the side of the car body, brake shoes pivotally connected to the rock-shaft for engaging the wheels, a bodily movable operating lever provided with a tooth pivoted to one end of the car for actuating the rock-shaft, a rack engaged by the tooth of the operating lever, and a resilient connection between the operating lever and the rock-shaft for holding the tooth of the operating lever in contact with the teeth of the rack.

21. The combination with a car body and a plurality of wheels at opposite sides of the car body, a rock-shaft arranged parallel to and supported on the side of the car body, brake shoes pivotally connected to each rock-shaft for engaging the wheels, an operating lever at opposite sides of the end of the car, a swinging arm having a floating fulcrum for attaching each of said operating levers to the car end, equalizing bars

connecting the operating levers, a tooth on each operating lever, a rack engaged by the tooth of each operating lever, and a resilient connection between each operating lever and the rock-shafts at the side of the car for holding the tooth of each of the operating levers in contact with the teeth of the racks. 5

22. The combination with a car body and wheels at each side of the car, a rock-shaft at each side of the car, a crank arm extending from the inner and outer end of each rock-shaft, brake shoes pivotally connected to the inner crank arm of each rock-shaft for engaging the wheels, an operating lever having a connection with each crank arm on the outer end of each rock-shaft, a floating pivotal connection between each operating lever and the car body, an equalizing connection between the operating levers, means for holding the operating levers when the brakes are set, and means for actuating both
 10 of the operating levers to release the brakes.

23. The combination with a car body and wheels at each side of the car, a rock-shaft arranged parallel to and supported on each side of the car, a crank arm extending from the inner and outer end of each rock-shaft, brake shoes pivotally connected to the inner crank arm of each rock-shaft for engaging the wheels, an adjustable rod pivoted to each crank arm on the outer end of each rock-shaft, a stirrup slidably mounted on each adjustable rod, resilient means on each adjustable rod within each stirrup for exerting pressure between each stirrup and the adjustable rod, an operating lever pivotally connected to each stirrup, a floating pivotal connection between each operating lever and the car body, and equalizing bars having their ends pivotally attached to each of the operating levers for connecting the operating levers together. 25

24. The combination with a car body and wheels at each side of the car, a rock-shaft arranged parallel to and supported on each side of the car, brake shoes pivotally connected to the rock-shafts for engaging the wheels, an operating lever disposed near each side of one end of the car, a floating pivotal connection for attaching each operating lever to the car end, equalizing bars connecting the operating levers, and pivoted thereto, resilient means interposed between the operating levers and the rock-shafts for holding the equalizing bars under tension, means for adjusting the tension between the rock-shafts and the equalizing bars, means for holding the operating levers when the brakes are set, and means for disengaging the operating
 40 levers from their holding means for automatically 45 releasing the brake shoes from the wheels. 50

25. The combination with a car body and wheels at each side of the car, a rock-shaft arranged parallel to and supported on each side of the car, a crank arm at the inner and outer ends of each of the rock-shafts, brake shoes adapted to engage the wheels having a pivotal connection with the inner crank arm of each rock-shaft, an operating lever pivotally connected to each of the
 60 crank arms on the outer ends of each of the rock-shafts, an equalizing connection between the operating levers, said equalizing connections comprising means when one of the operating levers is actuated for rotating one rock-shaft independently of the other rock-shaft. 65

26. The combination with a car body and wheels at each side of the car, a rock-shaft arranged parallel to and supported on each side of the car, a crank arm at the inner and outer
 70 75

end of each rock-shaft, brake shoes adapted to engage the wheels having a pivotal connection with the inner crank arm of each rock-shaft, a pair of operating levers each having a resilient connection with one of the crank arms on the outer ends of the rock-shafts, a pair of equalizing bars for connecting the operating levers together, said resilient connections and equalizing bars comprising means when one of the operating levers is actuated for initially rotating both of the rock-shafts simultaneously and then if required independently of each other to set the brakes.

27. The combination with a car body and wheels at each side of the car, a rock-shaft supported on each side of the car, each having a crank arm extending from their inner and outer ends, brake shoes adapted to engage the wheels, each having a pivotal connection with the inner crank arm of each rock-shaft, a pair of operating levers each having a resilient connection with one of the crank arms on the outer ends of the rock-shafts, means for adjusting the resilient connection between the operating levers and the crank arms on the outer ends of the rock-shafts, a pair of equalizing bars connecting the operating levers together, means for holding the operating levers when the brakes are set, and means for actuating the operating levers to automatically release the brakes.

28. The combination with a car body and wheels at each side of the car, a rock-shaft supported on each side of the car, each having a crank arm extending from their inner and outer ends, brake shoes pivotally connected to the inner crank arm of each rock-shaft, a pair of operating levers each having a floating fulcrum connection with the car body, a resilient connection between the operating levers and the crank arms on the outer ends of the rock-shafts, and equalizing bars for connecting the operating levers together.

29. The combination with a car body and wheels at each side of the car, a rock-shaft supported on each side of the car, each having a crank arm extending from their inner and outer ends, brake shoes pivotally connected to the inner crank arm of each rock-shaft, a pair of operating levers each having a floating fulcrum connected to the car body, a resilient adjustable connection between the operating lever and the crank arms on the outer ends of the rock-shafts, a pair of equalizing bars pivoted to and connecting the operating levers together, a tooth

on each operating lever, racks secured to the car body for engaging the tooth of each operating lever adapted to hold said operating levers when the brakes are set, and a crank-shaft having cranks adapted when manually actuated to disengage the tooth of each operating lever from the teeth of the racks to automatically release the brakes.

30. The combination with a car body and wheels at each side of the car, a rock-shaft supported on each side of the car, each having a crank arm extending from their inner and outer ends, brake shoes pivotally connected to the crank arms on the inner ends of each rock-shaft, a pair of operating levers, each having a swinging fulcrum pivoted to the car end, a pair of equalizing bars pivoted to and connecting the operating levers together, a tooth on each operating lever, racks secured to the car end adapted to engage the tooth of each operating lever for holding the operating levers when the brakes are set, a resilient connection between the operating levers and the crank arms on the outer ends of the rock-shafts for holding the tooth of each operating lever in the desired engagement with the teeth of the racks when the brakes are set, and a crank-shaft having cranks adapted when manually actuated to disengage the tooth of each operating lever from the teeth of the racks to automatically release the brakes.

31. The combination with a car body and wheels at each side of the car, a rock-shaft supported on the car body, brake shoes pivotally connected to the rock-shaft for engaging the wheels, an operating lever having a floating fulcrum pivoted to the car body for actuating the rock-shaft, and a resilient equalizing connection between the operating lever and the rock-shaft adapted to exert pressure on the brake shoes when the brakes are set.

32. The combination with a car body and a pair of wheels at each side of the car, a rock-shaft supported on each side of the car body, brake shoes pivotally connected to the rock-shafts for engaging the pairs of wheels on each side of the car, a pair of spaced operating levers each having a floating fulcrum pivoted to one end of the car body for actuating the rock-shafts, equalizing bars for connecting the pair of operating levers together, and a resilient connection between each operating lever and one of the rock-shafts for exerting pressure on the brake shoes when the brakes are set.

LOUIS G. MILLER.
